UNITED STATES PATENT OFFICE.

SHELDON E. JACKSON, OF WESTON, MICHIGAN, ASSIGNOR OF ONE-HALF
TO EPHRAIM B. LEE, OF WESTON, MICHIGAN.

WIRE FENCE.

No. 819,141.

Specification of Letters Patent.

Patented May 1, 1906.

Application filed September 22, 1904. Serial No. 225,492.

To all whom it may concern:

Be it known that I, SHELDON E. JACKSON, a citizen of the United States, residing at Weston, in the county of Lenawee and State 5 of Michigan, have invented a new and useful Wire Fence, of which the following is a specification.

This invention relates to wire fences, and has for its object to provide a novel form of 10 lock for connecting runner and stay wires at their point of crossing in a manner to secure a strong and durable connection between the fence-wires and to obtain a compact lock free from projections.

15 It is furthermore designed to form the lock from a single piece of wire which is capable of being initially wrapped about the fence-wires and then subjected to the action of dies to clamp the lock-wire upon the fence in its 20 completed condition.

With these and other objects in view the present invention consists in the combination and arrangement of parts, as will be herein-after more fully described, shown in the accompanying drawings, and particularly pointed out in the appended claim.

25 In the accompanying drawings, Figure 1 is an elevation illustrating a runner-wire and a stay-wire connected in accordance with the present invention. Fig. 2 is a sectional view on the line 2 2 of Fig. 1. Fig. 3 is a cross-sectional view on the line 3 3 of Fig. 2. Fig. 4 is a rear view of Fig. 1.

Like characters of reference designate corresponding parts in each and every figure of the drawings.

The present fence is made up of runner and stay wires, as usual, one of the runners being indicated at 1, while 2 designates a stay 40 crossing the runner at substantially right angles thereto and connected by means of the lock of the present invention, which is formed from a single length of wire. The middle portion 3 of the lock-wire extends obliquely 45 or diagonally across the joint between the runner and the stay, with one portion 4 lapped beneath the runner and thence upwardly, as at 5, and diagonally across the other side of the stay in substantial parallelism with the intermediate portion 3, the upper end of the wire being bent around the stay, as at 6, with its terminal inclined downwardly toward the runner. The other end portion of the lock is bent over the top of the

runner, as at 7, and then bent downwardly 55 across the front of the runner to the opposite side thereof in substantial parallelism with the portion 5, with its free extremity 9 bent or hooked around the rear side of the stay and directed toward the runner. 6c

From the foregoing description it will be noted that the middle portion of the lock-wire extends diagonally across the joint between the runner and stay in contact with the latter and is then looped in opposite directions across the front of the stay and the runner, whereby the latter is embraced at opposite sides of the stay in a snug and secure manner, while the extremities of the lock-wire are hooked to the stay and inclined 70 backwardly toward the runner, so as to avoid objectionable projections. This peculiar manner of bending the lock-bar produces two wraps diagonally across the front of the joint between the runner and the stay, with its 75 wraps extending in opposite directions, one from the under side of the runner and the other from the upper side of the runner, while the intermediate single wrap 3 extends diagonally across the stay at the rear of the 80 fence.

It will of course be understood that after the initial bending of the lock-wire around the stay and runner it is subjected to the action of dies, thereby to compress the lock 85 snugly about the fence-wires and into compact form, with its extremities drawn into snug engagement with the stay-wire, so as to avoid projections. In subjecting the lock-wire to the dies the runner and stay are of 90 course bent or kinked, as at 10 and 11, respectively, and the bends or coils of the lock-wire snugly embrace the bent or kinked portions of the fence-wires, so as to prevent end-wise looseness or play thereof, and hence 95 secure a tight and durable joint at the point of crossing of the fence-wires.

While the present lock has been shown and described with its end portions looped around the stay-wire, it is equally effective with its 100 ends looped about the line-wire, and I contemplate using both arrangements of the lock.

Having fully described the invention, what is claimed is—

A fence comprising crossed runner and stay wires and a lock-wire having its intermediate portion looped around the two 105

wires at their point of intersection and engaging the crotches formed thereby, the terminals of the lock-wire being looped around one of the fence-wires at points above and below the intermediate loop, and terminating on the same side of the fence-wire, and all of the loops being diagonally disposed relatively to the fence-wires.

In testimony that I claim the foregoing as my own I have hereto affixed my signature to in the presence of two witnesses.

SHELDON E. JACKSON.
